UNITED STATES PATENT OFFICE.

JOHN F. TEEHAN, OF BROCKTON, MASSACHUSETTS.

INNERSOLE.

Application filed March 28, 1923. Serial No. 628,260.

This invention has relation to innersoles for welt footwear of the general character illustrated and described in my Letters Patent No. 1,420,461 and No. 1,393,730, dated 5 June 20, 1922 and October 11, 1921, respectively.

In a shoe, such as illustrated in these patents, the innersole comprises two members at the shank, one of which is stitched to the 10 welt and the other of which is loose or free from the welt, thereby making the shoe flexible and comfortable to the wearer. More particularly the innersole, which forms the subject of this specification, is split at the 15 shank so as to provide the two members which are integrally connected along a line transversely of the innersole at approximately the ball thereof or at the juncture of the shank with the forepart of the inner- 20 sole.

The object of the invention is to provide a split shank innersole with a rib which is reinforced at the shank,—the invention comprising the innersole and the method of 25 making it.

On the drawings, I have illustrated the several steps which may be followed in forming an innersole in accordance with my process and for producing an innersole embody- 30 ing the invention.

Figure 1 represents an innersole, after the first operations have been performed thereon, to provide the innersole with an upstanding rib extending from the heel around the 35 shank and the forepart back to the heel again.

Figure 2 represents the innersole after the forepart thereof has been subjected to an inner channeling operation.

Figure 3 represents the innersole after it has been split and the reinforcing members have been turned up at the shank.

Figure 4 represents a longitudinal section on the line 4—4 of Figure 3.

Figures 5, 6 and 7 represent sections on the lines 5—5, 6—6 and 7—7 of Figures 1, 2 and 3 respectively.

(The innersole represented in the foregoing figures is preferably adapted for men's 50 shoes.)

Figure 8 represents an innersole blank after being subjected to the first operations of forming and turning the rib from heel to heel around the shank and forepart.

Figure 9 represents the same innersole 55 blank after it has been subjected to the second outside channeling and turning operation to provide a reinforcing member for the first-formed rib.

Figure 10 represents the blank after it 60 has been split both at the shank and at the toe end.

Figure 11 represents a section on the line 11—11 of Figure 10.

Figures 12, 13 and 14 represent sections 65 on the lines 12—12, 13—13 and 14—14 of Figures 8, 9 and 10, respectively.

(The innersole represented in Figures 8 to 14 inclusive is preferably adapted for women's shoes.)

An innersole, formed as herein described, is made of suitable material, such as sole leather or a substitute therefor which is capable of being channeled and split, the stock being of the necessary thickness according to the character of the shoe or other piece of footwear in which it is to be employed.

Referring first to Figures 1 to 7 inclusive, I have shown in plan view in Figure 1 an 80 innersole blank of suitable material which has been subjected to an outer channeling operation to form and turn up a rib 20 which extends from the dotted line a—a at the heel end of the shoe along the shank and forepart of the innersole back to the said dotted line, so that there is thereby provided a continuous rib to which the welt and the upper may be stitched. The forepart of the innersole is now subjected to an inner chan-

neling operation by which there is provided an inside channel 21 and a rib 22 which extends from what might be called the front end of the shank around the forepart, the two ribs 22 and 20 being spaced at their 85 bases far enough to afford ample between-substance through which the needle may

pass in stitching the welt and the upper to the innersole. The innersole is now split from the heel end forwardly to the dotted 90 line 4—4. The innersole is now split from the heel end forwardly to the dotted 95 line 4—4. The innersole is now split from the heel end forwardly to the dotted 100 line 4—4.

line $b-b$, as shown in Figure 3, at which the rib 22 terminates, the line of the split being indicated at $c-c$ in Figure 7. The feather along the shank on both sides thereof is thus split and it then coated with cement and upturned backwardly or inwardly from the edge so as to be cemented to the upturned rib 20, the reinforcing rib thus formed by the splitting and turning operation being indicated at 23. With the innersole thus formed, it will be seen that, during the welting operation wherein the welt and the upper are stitched to the innersole, the machine guide will engage the base of the rib 20 during the stitching operation along the shank and will enter the channel 21 and engage the base of the rib 22 during the operation on the forepart. The guide will enter and leave the channel without difficulty. The formation of the reinforcing ribs 23 affords a thickness of between-substance in the innersole approximating that at the forepart due to the formation of the inner channel and the rib 22 which results therefrom. An innersole as thus described is more especially applicable for men's footwear, although it will be seen that it may be utilized in making women's shoes as well.

In Figures 8 to 14, I have illustrated another embodiment of the invention which lends itself more especially to the formation of women's footwear. In this case, the innersole is first channeled along its outer edge to provide an upstanding rib 30 (turned inwardly or backwardly from the edge) which extends along the shank and the forepart continuously from heel to heel,—that is, from the dotted line $d-d$ along the shank and around the forepart and back to the dotted line. The feather of the inner sole may then be coated with cement, and the innersole is again channeled on the outside to form a second upstanding rib 31, which is cemented to the rib 30. If desired, the second channel may be cut, and the rib then coated with cement and turned inwardly or backwardly and compressed against the rib 30 so as to adhere thereto throughout its entire length. The innersole is then split from the heel end to the forward end of the shank as indicated by the dotted line $e-e$, the plane of the split being coincident with the base of the rib 31, as shown in Figure 4. If desired, the toe end of the innersole may be split towards the heel to approximately the line $f-f$ at the ball of the foot so as to afford two integrally-connected members at the toe end of the innersole as well as the two integrally-connected members at the shank.

In the case of both innersoles, as herein described, it will be seen that the innersole is split at the shank to afford two shank members which are connected at their for-

ward ends at approximately the ball of the shank but which are free from each other along the shank; and further that in each case there is a rib which extends continuously along both sides of the shank and the forepart, and which is reinforced at the shank by a second upturned rib member. In both innersoles, therefore, the rib-bearing shank member is loose from but integrally connected to the other shank member, and is provided along its side edges with a rib formed of two members, both upturned in the same direction backwardly or inwardly from the edge of the innersole, and preferably cemented and secured together. In the case of one innersole, the reinforcing rib member is formed by splitting the blank on a plane below the base of the first or inner rib member and then upturning the split edge, and, in the second case, by an outside channeling operation which is performed before the shank of the innersole is split. In one of the innersoles there is an inside channel, as in Figure 3, in the forepart of the innersole; whereas, in the case of the other innersole, the second outside channeling operation provides a reinforcing rib which is continuous from heel to heel and extends along the shank and around the forepart.

It is evident that the precise order of the steps taken in forming the innersole may be varied and that a definite sequence of operations is not necessary. For example, the reinforcing ribs at the shank of the innersole first herein described are formed by and simultaneously with the splitting operation, in which event the operation of turning the ribs upwardly and backwardly or inwardly is preferably performed subsequently; whereas, in the second described innersole, the splitting of the shank follows the channeling operation by which the outer reinforcing rib is formed. In this case, the rib-turning operation may follow the channeling and the splitting operations or it may occur between them, as most convenient.

What I claim is:—

1. An innersole comprising a blank having an integral feather, a rib upturned from the body of the blank and extending continuously along both sides of the shank and the forepart and turned up and back or inward from the edge, and a reinforcing rib also upturned from the body of the blank outside the first-mentioned rib on the shank portion of the innersole, the feather and the upturned ribs together being in thickness substantially equal to the body of the blank, and said innersole being split at its shank portion on the plane of the base of said reinforcing rib.

2. An innersole comprising a blank having an integral feather, a rib upturned from the body of the blank and extending continuously along both sides of the shank and

the forepart and turned up and back or inward from the edge, and a reinforcing rib also upturned from the body of the blank outside the first-mentioned rib on the shank

⁵ portion of the innersole, the feather and the upturned ribs together being in thickness substantially equal to the body of the blank,

said innersole being split at its shank portion and from the toe end substantially to the ball line on the plane of the base of said ¹⁰ reinforcing rib.

In testimony whereof I have affixed my signature.

JOHN F. TEEHAN.
